UNITED STATES PATENT OFFICE.

NOAH M. HUTTON, OF CHICAGO, ILLINOIS.

DOOR-LATCH.

No. 823,786.

Specification of Letters Patent.

Patented June 19, 1906.

Application filed April 8, 1904. Serial No. 202,208.

To all whom it may concern:

Be it known that I, NOAH M. HUTTON, a citizen of the United States, residing at Chicago, in the county of Cook and State of Illinois, have invented certain new and useful 5 Improvements in Door-Latches, of which the following is a specification.

My invention relates to fastenings for doors, being in the nature of an improved 10 latch of that general type wherein a hasp secured to the door coöperates with a staple and padlock on the casing, or vice versa.

The object of the invention is to provide a simple, strong, and convenient device which 15 may be operated at either side of the door and which shall be reversible for either right or left hand doors.

To this end my invention consists in a door-latch having the peculiarities of construction 20 and mode of manipulation substantially as hereinafter described, and defined in the claims.

My invention in its preferred form is illustrated in the accompanying drawings, where- 25 in—

Figure 1 is a front elevational view of the complete device in latched position, shown as applied to a door and its casing. Fig. 2 is a top plan view of the device shown in Fig. 1 30 with padlock applied and with the door and casing in horizontal section on substantially the median line of the device, and Fig. 3 is a view similar to Fig. 1 with the hasp in an unlatched position.

Referring to the drawings, 5 designates the vertical marginal portion of a door, and 6 designates the stationary casing alongside thereof. Secured to the former, as by screws 7, is a latch-plate 8, projecting from the face 35 of which latter near its opposite ends are upwardly-extending tongues 9, designed to constitute seats or supports for the shank 10 of a hasp, which is pivoted in and centrally of the plate 8 at one end and on its opposite 40 end carries a triangular-shaped head 11, adapted to partially enter a staple 12; projecting from the face of a plate 13, secured to the casing 6, as by screws 14. The head of the hasp has secured thereto and projecting 45 from its outer face a staple 15, which when 50 from its outer face a staple 15, which when the head is latched with the staple 12 over- lies the latter and may be locked thereto by an ordinary padlock 16. (Shown in Fig. 2.) The inner end of the shank 10 of the hasp is 55 fast on a pivot-pin 17, which latter has fast on its outer end a wing-nut 18 and fast on its

inner end another wing-nut 19, Fig. 2, which lies within a socket 20, formed in the inner face of the door.

With the parts in the position shown in Fig. 1 the hasp engages the staple, and the door is latched, while with the padlock 16 applied, as shown in Fig. 2, the door is locked. In order to open the door from its latched position, it is necessary only to give either 65 thumb-nut 18 or 19 a twist with the thumb and finger through a half-circle from the outside or the inside of the door, as the case may be, which swings the hasp over to the position shown in Fig. 3. An equal turn of either 70 thumb-nut in the opposite direction effects the latching of the door in an obvious manner. The tongue 9, remote from the casing, serves to support the hasp in idle position, and by making the plate 8 with duplicate 75 ends, as shown, and the hasp-head in duplicate on opposite sides of its longitudinal medial line the device is adapted for application for either right or left hand doors, and by making the hasp-operating means accessible 80 on both sides of the door the latter can be latched and unlatched with equal facility on either the outside or the inside. The triangular or wedge-shaped form of hasp-head insures a snug engagement with the staple, 85 thus preventing rattling and affording a latch combining great strength with small weight. The device is applicable to either sliding or hinged doors, and the described manner of operating the hasp in unlatching by swinging 90 the head around to a position where it lies away from the margin of the door is of importance, since it prevents all danger of the hasp catching upon objects passing in and out of the doorway and also prevents liability 95 of bending or breaking of the hasp through accidental slamming of the door.

While I have shown and described the hasp as applied to the door and coöperating with the staple in the casing, yet it will be evident that the relative position of these parts might be reversed and the hasp and its plate and operating devices applied to the casing and the staple to the door without departing from the principle or sacrificing any of the advantages of the invention.

I claim—

1. A reversible door-fastening of the character described, comprising, in combination, a latch-plate having hasp-supporting tongues 100 projecting laterally from each end thereof, respectively, a pivot-pin rotatably mounted 105

in said latch-plate centrally thereof and provided on each end with turning means, a hasp fast at one end on said pivot-pin and having a vertically-disposed flat triangular or spear-shaped head on its other end, and a horizontally-disposed staple secured to the casing and adapted to receive and seat the lower portion of said hasp-head, substantially as described.

- 10 2. A reversible door-fastening of the character described, comprising, in combination, a latch-plate having hasp-supporting tongues projecting laterally from each end thereof, respectively, a pivot-pin rotatably mounted 15 in said latch-plate centrally thereof and pro-

vided on each end with turning means, a hasp fast at one end on said pivot-pin, said hasp having at its other end a vertically-disposed flat triangular or spear-shaped head provided with a central horizontally-extending staple, and a horizontally-disposed staple secured to the casing and adapted to receive and seat the lower portion of said hasp-head and be locked to said hasp-head staple, substantially as described. 20

NOAH M. HUTTON.
